WILLIAM M. HINSON, OF LOCAL, ALABAMA.

LEG-BRACE.

1,228,113.

Specification of Letters Patent. Patented May 29, 1917.

Application filed June 19, 1916. Serial No. 104,480.

To all whom it may concern:

Be it known that I, WILLIAM M. HINSON, a citizen of the United States, residing at Local, in the county of Escambia and State 5 of Alabama, have invented certain new and useful Improvements in Leg - Braces, of which the following is a specification.

This invention relates to leg braces, and more particularly to a brace having an adjustable foot stirrup and especially adapted 10 to relieve the injured foot or knee from the pressure exerted by weight of the body.

One of the main objects of the invention is to provide a brace of the character stated 15 of simple construction and operation. Another object is to provide a brace which can be easily adjusted to relieve the foot or injured joint from all pressure. Further objects will appear from the following detailed description.

In the drawings:—

Figure 1 is a side view of the invention as applied,

Fig. 2 is a front view,

Fig. 3 is a section on line 3—3 of Fig. 2, and

Fig. 4 is a detail of the foot stirrup.

1 designates the upper leg inclosing member composed of top and bottom sheet metal 30 straps 2 and 3 and the leather body 4 secured to the same provided with suitable perforations 5 along its opposite edges adapted to receive the lace 6, a tongue 7 of soft leather being provided to project beneath the lace in the usual manner. A bar 8 is secured to the straps 2 and 3, at each side of member 1, and is provided at its lower end with an offset ear 9. This ear is 35 perforated to receive a rod 10, the upper end of which is offset and flattened to form an ear 11 which is secured to the top of the bar 8. The lower end of rod 10 is shaped to form an integral ear 12 which is pivotally secured to a similar ear on the upper end of 40 the rod 13 riveted in a tube 14 fixedly secured to the bar 15 rigidly mounted on the lower leg inclosing member 16, and similar to bar 8.

A threaded rod 17 is slidably mounted in 50 tube 14, and is provided at its lower end with an eye 18 which is pivotally connected to the upper end of the arm 19 of a foot stirrup 20. A nut 21 is threaded on rod 17 below the ear 15^a of bar 15, for the purpose 55 to be later disclosed.

The stirrup 20 is expanded at its center

portion, as at 22, and provided with a series of perforations 23. These perforations are adapted to receive rivets 24, or the like, by means of which the stirrup is fixedly secured to a steel plate 25 secured in the sole of a shoe 26. Of course, if desired, the stirrup may be secured to the shoe sole directly by means of screws threaded into the same through the apertures 23.

In using the brace, the upper member 1 is secured to the leg above the knee, and the lower member 16 is secured above the ankle and below the knee. The stirrup 20 is then adjusted, by turning the nuts 21 so as to force rods 17 downward out of the tubes 14, so as to force the shoe 26 downward and relieve the limb of the weight of the body. When walking the weight of the body will be transmitted to rods 10 and 13, 75 and by rods 17 and stirrup 20, to the shoe 26. By means of the nuts 21 the stirrup can be adjusted to suit the particular individual using it and to vary the amount of pressure which may be placed upon the injured foot 80 or joint so that, by gradually increasing this pressure, the joint may be gradually strengthened until the brace can be omitted entirely.

While I have described my brace as being 85 used for relieving an injured foot from pressure, it will be evident that it can be used equally well for relieving an injured ankle or knee from pressure, as will be clear from Fig. 1 of the drawings.

There may be variations made in the construction and disposition of the elements of my invention without departing from the field and scope of the same, and I intend to include all such variations in this application in which a preferred form only of my invention is disclosed.

What I claim, is:—

In a brace of the character described, an upper leg engaging member, a flat bar secured to each side thereof and turned outward at its lower end to provide an integral ear, a rod inserted through said ear and fixedly secured at its upper end to said bar, a lower leg engaging member, a flat bar secured to said lower member at each side thereof and turned outward at its lower end to provide an integral ear, tubes secured on each of said side bars of the lower member above the ear thereof, externally threaded rods slidably mounted in said tubes and through said ears, a stirrup pivotally se-

cured to the lower end of said rods, nuts
threaded on said threaded rods and bearing
against the ears of the bars of said lower legs
engaging members whereby said rods may
5 be forced out of said tubes by threading the
nuts onto the rods, and rods fixedly secured
in the upper portions of said tubes and piv-
otally secured at their upper ends to the

lower ends of the rods carried by said upper
leg engaging member.

In testimony whereof I affix my signature
in presence of two witnesses.

WILLIAM M. HINSON.
